(57) **CLAIM**

The ornamental design for a flex-loc clamp mirror light, as shown and described.

DESCRIPTION

The drawing is a perspective view showing my design for a flex-loc clamp mirror light, which includes mirror, LED, flex-loc, cylinder, on/off switch, and clamp.

FIG. 1 is a bottom, left side perspective view of a flex-loc clamp mirror light showing my new design; and,

FIG. 2 is a top, right side perspective view thereof.
